UNITED STATES PATENT OFFICE.

GUSTAVE E. VILLARET, OF LEONIA, NEW JERSEY, ASSIGNOR TO WILLIAM R. NOE & SONS, A COPARTNERSHIP, OF NEW YORK, N. Y.

DESIGN FOR A PEDESTAL FOR A LAMP.

Application filed June 5, 1926. Serial No. 17,954. Term of patent 7 years.

To all whom it may concern:

Be it known that I, GUSTAVE E. VILLARET, a citizen of the United States, residing at Leonia, in the county of Bergen and State of New Jersey, have invented a new, original, and ornamental Design for a Pedestal for a Lamp, of which the following is a specification, reference being had to the accompanying drawing, forming part thereof, in which—

Fig. 1 is a front elevation showing my new design;

Fig. 2 is a plan view for the purpose of showing the contour.

I claim:

The ornamental design for a pedestal for a lamp, as shown.

GUSTAVE E. VILLARET.
